(57) **CLAIM**

The ornamental design for a sitting pad with holster, as shown and described.

DESCRIPTION

FIG. 1 is a top perspective view of an embodiment of the sitting pad with holster of the present invention;

FIG. 2 is a front elevation view thereof;

FIG. 3 is a right side elevation view thereof;

FIG. 4 is a rear elevation view thereof;

FIG. 5 is a left side elevation view thereof;

FIG. 6 is a top plan view thereof; and,

FIG. 7 is a bottom plan view thereof.

The evenly spaced broken lines shown in the drawings are directed to environment, are for informational purposes only, and form no part of the claimed design. The long and short broken lines are boundary lines which define the bounds of the claimed design. These boundaries do not exist in reality in the article embodying the design. It is understood that the claimed design extends to these boundaries but do not include the boundaries. The evenly spaced broken lines within the stippled feature of FIG. 7 represent stitching that does not form part of the claimed design.

The sitting pad shown fully in FIG. 1, is shown enlarged and fragmentary using symbolic break lines in FIGS. 2–7 solely to allow for larger showings of the features included in the claimed design.
